RELEASABLE HOLDING ARMS FOR DOOR CHECKS

David R. Lasier, Chicago, Ill., assignor to Norton Lasier Company, Chicago, Ill., a corporation of Illinois

Application May 27, 1938, Serial No. 210,353

6 Claims. (Cl. 189—49)

This invention relates to an improved holding device of the type usually applied to doors, windows and the like, for holding them in a predetermined open position and which is affected by heat at a predetermined temperature causing the holding means to become ineffective whereby the door may be free to close automatically, cutting off drafts and preventing or deterring the spread of fire. The releasing means may depend for its action upon a fusible element or link of well known construction.

An object of this invention is to provide a releasable holding device for doors or the like, which will effectively hold a door in any desired open position and which will readily and quickly release the door when subjected to heat of a predetermined temperature.

Another object of this invention is to provide a releasable holding device of such construction that currents of heat passing in either direction through the passageway will more quickly reach the releasing mechanism and effect a rapid release of the door.

These and other objects not specifically enumerated will readily appear to one skilled in the art as the following description proceeds.

In the accompanying drawings—

Figure 1 is a plan view of a door closing and checking device of the surface type, equipped with a holding arm construction in accordance with this invention;

Figure 2 is an elevational view of the device shown in Figure 1;

Figure 3 is an enlarged perspective view of a portion of the holding arm showing the construction of the friction head and part of the releasing mechanism;

Figure 4 is an enlarged plan view of a holding device constructed in accordance with this invention, showing it in released position; and

Figure 5 is an enlarged perspective view of a portion of the holding arm showing the fusible link and its relation to the releasing device.

By referring to the drawings, it will be noted that the invention here illustrated is embodied in a holding arm which consists of a crank arm 10 and a forearm 11, the first of which is connected at one end 12 to the spindle 13 of a door closing and checking device 14. The checking device per se forms no part of this invention and may be of any suitable type or, in some instances, omitted altogether. The device here illustrated is the usual surface type door check and is connected by means of a bracket 15 to the upper surface of the door 16 so as to be carried thereby

when the door is moved to open position on the hinges 17.

The outer end of the crank arm 10 is provided with a spiral faced friction head 18 and is of substantially the same construction as that constituting the holding device disclosed in applicant's Patent No. 1,826,553, of October 6, 1931.

The forearm in the illustrated embodiment of the invention has at its outer end a friction head 19, which is best illustrated in Figure 3 and is pivoted as by a pin 20 to the socket member 21 equipped with a set screw 22. The rod 49 is retained in the member 21 in any desired adjusted position by the holding action of the set screw and has provided at its other end, a universal joint 23 having horizontal and vertical pivots for connecting the same to the bracket 24 which is attached to the door frame. The above described features of the forearm are substantially the same as those illustrated in applicant's Patent No. 1,826,553 above referred to, and thus the forearm is capable of acting in substantially the same way, it being understood that the friction head on the outer end is provided with a frictional face adapted to have cooperative engagement with the frictional face on the head 18 of the crank arm.

The novelty of this invention resides in certain structural features which are best illustrated in Figures 3 to 5, inclusive. The friction head 19 is provided with a pivot lug 25 and, in addition, a lug 26 having right angle faces. Pivotedly connected by means of a pin 27 to the pivot lug 25 is the element 28. This element is provided with a projecting portion 29 having an inside right angle surface 30 adapted to embrace the right angle faces of the lug 26, and also having an outer face 31.

The friction head 19 is also provided with a pair of ears 32 which loosely embrace the sides of the control lever 33 which is pivotally held adjacent the end thereof by the pin 34 passing through the ears of the lever. The control lever may be substantially straight sided as shown, and the under surface 35 adapted to abut the outer face 31 of the projecting portion 29. The opposite end of the lever is preferably round, as shown at 36.

The arm 11 is provided at its inner end with a pair of ears 37 adapted to pivotally hold the locking pawl 38 by means of the pin 39. The locking pawl 38 has an extension 40 to which is attached a coil spring 41 by means of the hook 42 passing through the slot 43 and held by the pin 44. The locking pawl is also provided with a curved abutting surface 45 adjacent the pivot 39.

adapted to overlie the round end 36 of the control lever 33.

The control lever 33 is provided on its outer surface with a pin 46 which is adapted to hold 5 one end of the fusible link 47. The link has eyes 49 at its ends for engaging the pin and spring, respectively. The pin passes through one of the eyes and the hook 48 on the end of the spring 41 passes through the other eye. The 10 length of the fusible link 47 and the spring 41 are such that the curved abutting surface of the locking pawl 38 is held in intimate engagement with the round end 36 of the control lever 33 under the tension of the spring 41 in the 15 manner shown in Figure 1. The various parts are so constructed that when the curved abutting surface 45 of the locking pawl 38 is in contact with the curved end 36 of the control lever, the inner surface 35 of the lever 33 is in close contact with the outer face 31 of the element 28, and the inner right-angle faces 30 are in close contact with the right-angle faces of the lug 26. Consequently, when the parts are in assembled position as shown in Figure 1, the 20 element 28 is held rigidly relative to the friction head 19 whereby, in effect, these parts are a single rigid member.

It will be noted that the pivoted connection at 34 is quite loose, that is, the opening in the 25 control lever 33 through which the pin 34 passes is considerably larger than the circumference of the pin and the space between the ears 32 is greater than the width of the control lever 33. The play in this connection is sufficient to allow 30 the arm 11 to pivot at 20 for the purpose of adjustment without in any way disturbing the rigidity of the pivotal connection 27 between the friction head 19 and arm 11, when in the position shown in Figure 1.

40 It will also be noted that when the under face of the lever 35 is in contact with the face 31 of the element 28, the round end 36 of the lever cannot be inserted under the curved surface 45 of the locking pawl 38 without exerting pressure 45 on the lever, causing it to flex and press tightly against the face 31. Consequently, the lever, when in the position shown in Figure 1, is held under tension and when the locking pawl 38 is released the lever will snap open, partly as a 50 result of this tension, and assume the position shown in Figure 4.

In operation, the holding device is mounted in the customary manner, with the parts arranged as shown in Figures 1 and 2, whereby 55 the elements 19 and 28 will be rigidly held together in a manner to cause these parts to function as a unitary arm. In this event, the holding device, comprising the cooperating friction faces, functions in the manner of the device in 60 applicant's Patent No. 1,826,553 to hold the door open in any predetermined position.

In the event of fire, such that the fusible link 47 will be fused, the portions of the link will become separated, breaking the tension in the 65 spring 41 and leaving the locking pawl 38 free to disengage the surface 31 of the element 28. Under such circumstances, even though the friction faces are firmly bound in a manner to hold 70 the door, the independent pivot provided on the pin 27 acts as a substitute pivot and permits the arms to pivot relative to each other whereby the door is free to swing shut.

If the device is used in combination with a 75 door closing mechanism, whether of the check-

ing type or of any other type, this mechanism will allow the door to shut in the desired manner. It is obvious that the invention has application on all sorts of closures, such as doors, windows and the like, and that the device when 5 installed is connected to a closure, such as a door at one end, and to a stationary part, such as a sill at its other end; and accordingly, the invention is to be construed broadly and as covering all such installations. However, for the 10 purpose of clarity, the applicant has defined his device as connected between a door and door sill, but these terms are to be considered as covering all similar means.

One of the advantages of having the fusible 15 link located in close proximity to the door sill becomes more apparent when the course of hot air currents is considered. As is well known, fire starting in one room will quickly heat the upper air in that room to a high temperature. This air expands and rapidly spills into adjoining rooms and halls through open doorways. The average door sill being somewhat lower than the ceiling of the room, the hot air in expanding 20 will be forced under the door sill. After it has passed under the door sill, it may again quickly rise to the ceiling; consequently, the temperature of the air in the immediate vicinity of the door sill may be higher than the air a short distance from it. By locating the fusible 25 element nearer the door sill, it will be more quickly contacted by the hot air regardless of which direction the hot air is coming from; that is, whether it is coming from the side on which the releasing device is located or from 30 the other side.

What is claimed is:

1. A holding device adapted to be pivotally connected between a door and door sill, respectively, comprising, in combination, an arm having a friction face on one end, an element having a cooperating friction face pivotally connected to said end of said arm, a second arm independently pivoted at one of its ends to said element, releasable means for normally holding inactive said second-named pivot comprising a lever independently pivoted to said element and adapted to have holding engagement with a portion of said second arm, and means including a fusible link connected at one of its ends to said lever and at the 45 other of its ends to a member carried by said second arm adjacent the other end thereof, said means being so disposed as to locate said fusible link adjacent said other end of said second arm.

2. A holding device adapted to be pivotally 50 connected between a door and door sill, respectively, comprising, in combination, an arm having a friction face on one end, an element having a cooperating friction face pivotally connected to said end of said arm, a second arm independently 55 pivoted at one of its ends to said element, releasable means for normally holding inactive said second-named pivot comprising a lever independently pivoted adjacent one of its ends to said element and extending to a location adjacent the 60 other end of said second arm, and means adjacent said other end of said second arm and carried by said second arm and lever, respectively, including a fusible link and serving to maintain said lever in holding position.

3. A holding device adapted to be pivotally connected between a door and door sill, respectively, comprising, in combination, an arm having a friction face on one end, an element having a cooperating friction face pivotally connected to 70

5 said end of said arm, a second element pivotally connected to said first-named element, a second arm pivotally connected to said second element, releasable means for normally holding inactive
5 said pivot between said first and second elements so as to provide a rigid connection therebetween comprising a lever pivotally connected to said first element and adapted for holding engagement with a portion of said second element, said lever
10 extending to a location adjacent the opposite end of said second arm, and means adjacent said opposite end of said second arm carried by said arm and lever, respectively, including a fusible link and serving to maintain said lever in holding position.
15 4. A holding device adapted to be pivotally connected between a door and door sill, respectively, comprising in combination, an arm having a friction face on one end, an element having a
20 cooperating friction face pivotally connected to said end of said arm, a second element pivotally connected to said first-named element, a second arm pivotally connected to said second element, releasable means for normally holding
25 inactive said pivot between said first and second elements so as to provide a rigid connection therebetween comprising a lever pivotally connected to said first element and adapted for holding engagement with a portion of said second element,
30 said lever extending to a location adjacent the opposite end of said second arm, a locking pawl carried by the opposite end of said second arm for engaging the end of said lever, and means including a fusible link for normally maintaining said
35 lever.
40 5. A holding device adapted to be pivotally connected between a door and door sill, respectively, comprising, in combination, an arm having a friction face on one end, an element having a

cooperating friction face pivotally connected on a vertical axis to said end of said arm, a second element pivoted on a vertical axis to said first element, a second arm pivoted on a horizontal axis to said second element, releasable means for normally holding inactive said pivot between said first and second elements so as to form a rigid connection therebetween comprising a lever independently pivoted at one of its ends with slight universal movement to said first element and extending to a location adjacent the opposite end of said second arm, and means adjacent said opposite end of said second arm carried by said arm and lever, respectively, including a fusible link and serving to maintain said lever in holding position.
5 6. A holding device adapted to be pivotally connected between a door and door sill, respectively, comprising in combination, an arm having a friction face on one end, an element having a cooperating friction face pivotally connected on a vertical axis to said end of said arm, a second element pivoted on a vertical axis to said first element, a second arm pivoted on a horizontal axis to said second element, releasable means for normally holding inactive said pivot between said first and second elements so as to form a rigid connection therebetween comprising a lever adapted for engagement with a portion of said second element and independently pivoted at one of its ends with slight universal movement to said first element, said lever extending to a location adjacent the opposite end of said second arm, a locking pawl carried by the opposite end of said second arm for engaging the end of said lever, and means including a fusible link for normally maintaining said locking pawl in holding engagement with said lever.
